PROTECTIVE SHEATH FOR MEDICAL AND SURGICAL USE

Edward F. Bowman, Boston, Mass., assignor to
Edwin T. Wyman, Brookline, Mass.

Application March 21, 1941, Serial No. 384,436

2 Claims. (Cl. 128—294)

The present invention relates to coverings in the nature of finger cots for protection of a surgeon's fingers against infection when inserted into localities containing disease germs, and for analogous uses. Its object is to provide such coverings for single members, as distinguished from the connected fingers of a surgical glove, of substantially less thickness than the material of surgeons' gloves and having means forming an integral part thereof for binding them on the finger. A further object is to provide a chamber in the closed extremity of such sheath, partially subdivided from the main body of the sheath, but communicating therewith, adapted to receive a fluid, such as an antiseptic or cleansing liquid to serve as an additional safeguard against infection.

The drawing illustrates the principles of the invention in a generic way without reproducing the exact dimensions or form of a sheath designed for any specific finger.

Fig. 1 of the drawing is a side elevation of the protector;

Fig. 2 is a longitudinal section thereof;

Figs. 3 and 4 are views similar to Fig. 2 showing other forms of the protector.

My protective device is made of thin, exceedingly flexible and resilient material, preferably a vulcanized composition of natural rubber, or analogous compound of so called synthetic rubber. The precise composition and methods of making it are not of the essence of the invention, and all substantial equivalents of the substances herein named may be used within the scope of the protection which I seek, and the article may be made by any suitable method of manufacture.

The protective cover or sheath here shown is made with a body portion *a* and an end chamber or sac *b*. The body portion is of suitable length and diameter to receive, and fit smoothly upon, the finger for which it is designed, without being unduly stretched. It is of generally cylindrical shape. The material forming its side walls is thin; of a thickness approximating that of paper, i. e., in the order of from two to eight thousandths of an inch. A constriction *c* is formed in the sheath to constitute a retaining band adapted to bind the sheath on the finger by contractile force over a zone of narrow width. Such constriction may be located at the open end of the sheath, as shown in Figs. 1, 2 and 3, or at any desired distance from such open end, as shown in Fig. 4. In any case it is far enough from the closed end to surround the finger with the de-

sired gripping effect. The constriction *c* is made of a diameter enough smaller than that of the main body of the sheath to have the desired effect. It may be of greater thickness than the thin sheath walls, as shown in Fig. 2, or of the same thickness, as shown in Figs. 3 and 4. When made of greater thickness, it is not essential that the constriction be at the open end of the sheath; the constriction intermediate the ends may 10 equally well be thicker than the contiguous walls. In any case the rim of the end opening is preferably reinforced by a bead *d* of substantially circular cross section.

When the sheath is placed on the finger, the constriction is stretched to much larger than normal diameter, and its natural resilience causes it to embrace the finger with sufficient force to prevent the sheath from slipping off.

The sac or chamber *b* is united with the body 20 part by a neck *e* of reduced diameter. Such neck is formed by an annular ring or band in integral union with the walls of the body and sac, which are of tapering form adjacent to their junction points. The neck zone may be of substantially greater thickness than the adjoining walls, as 25 shown in Fig. 2, or it may be of the same thickness, as shown in Fig. 4. In either case it resists enlargement, and the force of such resistance is of course greater in the case of the thickened 30 formation.

A passage *f* extends through the neck into the interior of the sac *b*. Such passage is too small to permit entrance into the interior of the sac of a finger large enough to fit the body part of 35 the sheath, but it provides ample space for the passage of fluid. If the sac is filled with an antiseptic solution before the finger is inserted into the protective sheath, the end of the finger will block the passage *f* in some measure, preventing 40 a free flow of the solution but permitting a slow seepage. The constriction or band *c*, however, embraces the finger tightly enough to prevent escape of the fluid from the open end of the sheath.

45 What I claim and desire to secure by Letters Patent is:

1. A protective sheath having flexible expandible resilient walls of a thickness in the order of a few thousandths of an inch, closed at one end 50 and open at the other end, the sides of the sheath being shaped to form a constriction which, when the sheath is free of external or internal stress is of substantially smaller internal diameter than the contiguous portions of the sheath and located 55 between the ends at a distance from the closed

end such that it will serve as a binder to retain the sheath on an inserted member.

2. A protective sheath having flexible elastic and resilient walls of slight thickness closed at one end and open at the other end, having when in its normal unstressed condition a constriction intermediate the open and closed ends and at

considerable distances from both, the inside diameter of the sheath at both sides of the constriction being substantially the same and substantially larger than the smallest diameter of the constriction.

EDWARD F. BOWMAN.
